Letter Patent No. 1363 Dated Dec 18 1860

The schedule referred to in these Letters Patent, and making part of the same
Follows where it may concern:

Be it known, that I, Jacob Steffe, of the City of
Philadelphia, State of Pennsylvania, have invented or produced a new and original
design for the front of a confectionery store, known as the "Golden gate," and I hereby
declare the accompanying drawing and following explanation of the same to
form a full, clear and exact description of the said design.

Fig. 1 of the drawing represents one of the side plates of the store

Wls. 1363

Fig. 2, the upper front plate of the same.

Fig. 3, the back plate.

Fig. 4, the bottom plate.

Fig. 5, the ash pit plate, and

Fig. 6, one of the feet.

The side plate, Fig. 1, is edged with a plain moulding and has a large oven door A, a small door B, and a panel C, both doors and panel unedged with plain mouldings including the foliated ornamental represented in the drawing.

The upper front plate Fig. 2, is also edged with a plain moulding and has two doors with foliated ornaments of a character similar to that on the door B, of the side plate Fig. 1. The back plate Fig. 3, has three panel each containing a foliated ornament as represented in the drawing.

The bottom plate, Fig. 4, is edged with a moulding having springs situated at intervals, and the ash pit plate Fig. 5, has on three of its edges moulding ornamented with the projections shown in the drawing. The view Fig. 6, fully illustrates the ornamentation of one of the feet of the stove.

I claim the combination of ornamental figures and forms represented in and by the accompanying drawing the whole forming plates for a cooking stove.

Intestimony whereof I have signed my name to this specification in the presence of the subscribing witnesses.
